UNITED STATES PATENT OFFICE

2,014,094

MOCCASIN

Daniel W. Wiggin, Yarmouth, Maine, assignor to
 The Abbott Company, Yarmouth, Maine, a corporation of Maine

Application September 24, 1930, Serial No. 484,037

6 Claims. (Cl. 36—11)

This invention relates to footwear and particularly to double structure shoes or boots where extra waterproofness or warmth is desired. Articles of this type have been proposed as in effect 5 a shoe within a shoe, but obviously the doubling of any ordinary shoe structure must make it very stiff and rigid particularly in the seams.

The particular fields of usefulness for footwear of this type are those in which much actual walking or climbing must be done and under such conditions the wearer needs a maximum freedom of 10 foot action as life and limb are frequently dependent on sure footedness and stiff or clumsy footwear is fatiguing in ordinary walking and a handicap in emergency footwork.

My present invention contemplates a combination of different types of footwear so that in a single structure I have the essential factors of two old and well known types built into a novel 15 unit of greatly increased advantage for the purposes suggested.

In addition to the difficulties of providing a strong waterproof boot or shoe of the double type, there is the ever present demand for neatness and 20 style in appearance which means in most cases that the article must appear as of the usual modish type while having unusual utilitarian structural features so embodied as not to detract from its external appearance.

30 My concept is essentially the combination of two distinct members, an outer and an inner. The inner member is a moccasin of true type; that is, with the vamp extending under the sole of the foot so that the same piece forms both the sides 35 and the bottom. The top may consist of a toe piece sewn to the upturned edges of the vamp with a U seam as is customary with most moccasins of the American Indians, or the vamp itself may be continued up over the foot and its edges stitched 40 together with a T-shaped seam, as was used by certain tribes of Indians (the Chitemacha of Louisiana, the Sauk and Fox of Oklahoma), and to a certain extent by modern moccasin makers.

The outer member is the vamp of a shoe of ordinary 45 external appearance and may be of Good-year welt, McKay, Stitchdown, or other methods, the Stitchdown construction being preferred.

The advantages of a moccasin next to the foot 50 are great. The foot is cradled in the vamp and the seam is high and above the tread of the foot and above the ordinary water line.

For the purposes of illustration and discussion I have shown in the accompanying drawings, an embodiment of my invention in which a moccasin 55 is given the appearance of an ordinary type

of shoe, that shown being a Stitchdown. In the drawings:

Fig. 1 is a general view of such a shoe having the toe reinforcing portion rolled back to expose the toe of the moccasin and its assembly. 5

Fig. 2 is a view of the toe portion completed.

Fig. 3 is a section on the line 3—3, of Fig. 2.

Fig. 4 is a view similar to Figure 1, showing a moccasin member of different type.

Fig. 5 is a cross section on the line 5—5, Fig. 4, 10 and

Fig. 6 is a view of the pattern of the inner or moccasin member.

Referring to the structure shown in Figs. 1 to 3, inclusive, the vamp of the moccasin member is 15 indicated at 1, united at 2 to a toe member 3, as in any moccasin. The sole 4 is stitched as at 5 to the vamp. This may be done either before or after sewing the seam 2.

On the structure thus formed, which is a 20 moccasin having a sole with edges extending somewhat beyond the sides of the moccasin, the second or external element 6 is placed. It may be of any type or pattern. It is, however, shown as fastened as at 7 by the Stitchdown method to the 25 projecting edges of the sole 4. An additional sole may be applied as desired.

It will be noted that in such a structure the moccasin element becomes a free cradling encasement for the foot, and that the use of innersole, 30 welt and bottom filler is avoided as is the case with all moccasin construction, thereby giving the footwear greater flexibility, lightness and comfort.

In building such a composite shoe structure the 35 use of the U-shaped toe seam involves a distinct difficulty in the prominence of the seam 2. In the moccasin this is so characteristic as not to be at all objectionable, but in fact a feature looked for as indicative to the buyer of the true 40 moccasin product.

In combination, however, this characteristic seam is so prominent as to be a problem as the overlying toe member 6 which must be tightly fastened tends to show any ridge or projection in 45 the underlying structure.

According to my invention I avoid this difficulty and attain further advantage by providing a layer 50 8 on the toe piece 3 within the lifted seam 2. This may be of any material but according to my invention is a plastic waterproof filler such as has been heretofore used as a sole filler, but preferably more elastic and more waterproof. It is to be noted that the top of the foot and the base of the instep are areas particularly subjected to 55

moisture under pressure as where the wearer is walking through wet grass or snow.

In practice the outer shoe member 6 is cemented to the filler 8 and toe member 2 and so much of the vamp 1 as it contacts. In fact, the waterproof cement is extended to all contacting parts as to the sole 4 and the seams 7 when the member 6 is stitched down.

The difficulty involved in the use of the U-seam may be entirely avoided by enlarging the vamp so that a separate toe piece is unnecessary, the upturned edges of the vamp being united by a T-shaped toe seam, thus forming a combined or integral vamp and toe piece (see Figs. 4 to 6). In the form shown in Figs. 4 to 6, inclusive, the moccasin member 11a is of the general pattern indicated in Fig. 6, the edges of the vamp 11 being united by a longitudinal seam 12 and transverse seams 13 and a toe seam 18. The sole 4 is applied in the usual way by stitches 5 and the outer shoe member 6 lasted over the moccasin and stitched or otherwise fastened as at 7. The outer shoe member 6 may be cemented to the moccasin member 11 all as hereinbefore described.

The structures herein shown constitute a new type of footwear combining a member of true moccasin type while outwardly presenting a shoe of conventional style. These offer distinct advantages, in some respects even beyond the combined factors of the two essential elements of which they are made. These advantages are: (1) Like a moccasin they have no innersole, welt or bottom filler. They are, therefore, flexible, light-weight, and offer a permanently flat and uniform bearing for the foot. (2) They offer the cradling support of the true moccasin. (3) The outer element 6 overlies the seam of the moccasin, protecting it from ripping and also from leaking. (4) The outer element being fastened to the sole at 7 prevents water from entering between the vamp cover 6 and the seam of the moccasin. (5) The sealing together of the two elements cementitiously provides an additional factor increasing their wearing and water turning powers. (6) Since the weakest point of the moccasin is at the seam 2 at the top of the foot and the weakest point of the shoe is at the seam 7 where the upper joins the sole, in these structures, the strong points of the moccasin are opposite the weak points of the shoe, and the strong points of the shoe protect the weak points of the moccasin. (7) The outer shoe offers great freedom in the way of design and decoration.

As above suggested, the elements of the combination may be of various design or pattern and

may be variously assembled, those shown being merely illustrative and suggestive of such changes and modifications as will readily occur to those skilled in this art.

What I therefore claim and desire to secure by Letters Patent is:—

1. An article of footwear comprising a member of moccasin construction, a sole, a toe filler for the fore part of the moccasin member, and an outer vamp cover overlying the moccasin member and 10 marginally united to the sole.

2. An article of footwear comprising a member of moccasin construction including seamed vamp and toe piece members, a sole attached to the bottom of the vamp, a filler over the toe piece within 15 the seam thereof, and an exterior member overlying the vamp of the moccasin member and marginally united to the sole.

3. An article of footwear comprising a member of moccasin construction including a vamp and 20 toe piece seamed together, a sole attached to the bottom of the vamp, a filler over the toe piece within the seam thereof, and an outer vamp cover overlying the moccasin member, the vamp covering being cementitiously united to the moccasin 25 and filler.

4. An article of footwear, comprising a member of moccasin construction, including a vamp and a toe piece seamed together, an outer vamp cover overlying the vamp and toe piece, and a 30 sole seamed to the upper, the seam uniting said toe piece and said vamp being substantially spaced from the seam uniting said outer vamp cover to said sole.

5. An article of footwear, comprising a member 35 of moccasin construction, including a vamp extending continuously around the foot as an integral tread portion, a toe piece seamed to said vamp a substantial distance above the tread portion, an outer vamp cover overlying the vamp and 40 toe piece, a sole seamed to said outer vamp cover, the seam uniting said toe piece and said vamp being substantially spaced from the seam uniting said outer vamp-cover to said sole.

6. An article of footwear, consisting of a toe 45 piece and a vamp extending continuously around the foot as an integral tread portion and seamed to each other a substantial distance from the tread portion, a sole attached to the tread portion and an outer vamp cover overlying the toe 50 piece and vamp above said sole, and seamed to said sole, the seams uniting said toe piece and said vamp being substantially spaced from the seam uniting said outer vamp cover to said sole.
